(57) **CLAIM**

The ornamental design for a lavatory, as shown and described.

DESCRIPTION

FIG. 1 is a perspective view from the left side and above of the lavatory showing my new design;

FIG. 2 is a top plan view thereof;

FIG. 3 is a front elevational view thereof;

FIG. 4 is a left side elevational view thereof, the right side elevational view being a mirror image thereof;

FIG. 5 is an elevational view of 45° to the front elevational view;

FIG. 6 is a rear elevational view thereof;

FIG. 7 is a bottom view thereof; and,

FIG. 8 is a vertical sectional view on section line 8—8 shown in FIG. 2.
